UNITED STATES PATENT OFFICE.

ALBERT F. PRENTICE, OF WORCESTER, MASSACHUSETTS.

DRILLING-MACHINE.

SPECIFICATION forming part of Letters Patent No. 340,615, dated April 27, 1886.

Application filed February 23, 1886. Serial No. 192,818. (No model.)

To all whom it may concern:

Be it known that I, ALBERT F. PRENTICE, a citizen of the United States, residing at Worcester, in the county of Worcester and 5 State of Massachusetts, have invented certain new and useful Improvements in Upright Drilling-Machines; and I declare the following to be a description of my said invention sufficiently full, clear, and exact to enable 10 others skilled in the art to which it appertains to make and use the same, reference being had to the accompanying drawings, which form a part of this specification.

The object of my present invention is to provide facilities in an upright drilling-machine 15 whereby either the head or the quill can, at the pleasure of the operator, be put in connection with and operated by the power feeding mechanism, so that the drilling-tool can be fed up 20 or down by movement of the head or by movement of the quill, or both, as most convenient or desirable for the work. This object I attain by mechanism organized for operation substantially as hereinafter explained, 25 the particular subject-matter claimed being hereinafter definitely specified.

In the drawings, Figure 1 is a side view of 30 such parts of an upright drilling-machine as will illustrate the nature of my invention. Fig. 2 is a view of the opposite side of the head and quill on a somewhat larger scale. Fig. 3 is a horizontal section through the head, quill, and standard; and Fig. 4 shows a modification of the shifting-gear.

35 In reference to parts, A denotes the standard, post, or supporting-frame.

B indicates the head, mounted in the usual manner upon guideways *a* on the front of the frame A, to move up and down thereon.

40 C indicates the feed-quill, which works up and down through the front part of the head, and supports or carries the drill-spindle D, which latter is constructed and operated in the usual manner, the rotative motion being 45 imparted thereto by gears D' from the shaft E.

The mechanism for driving shaft E, which is not herein shown, may be made of the ordinary well-known construction, as it forms no part of my present invention.

50 F denotes the feed-shaft, arranged horizontally across the head B to turn in bearings *b*.

Upon said shaft is mounted the loose-running worm-wheel G, provided with clutch-teeth on its side for locking with the clutch-hub H, which latter is fitted to the shaft with a spline 55 or feather, *h*, to prevent independent rotation between the shaft and hub, so that when the clutch is thrown in the movement of wheel G will cause the movement of the shaft F.

The worm-wheel G is operated by the arm 60 or screw *i* on shaft I, in connection with the usual well-known devices, such as gears I', spindle I², pulleys and gears at I⁴, and the hand-wheel I⁵, as shown. A rack, C', is fixed on the quill C, and a rack, A', is also fixed in 65 or upon the post or frame A. Meshing with the rack C' is a gear or pinion, J, rigidly fixed upon or integral with a sleeve, J', that is mounted to turn loose on shaft F, and which sleeve extends through the bearing *b*' in the 70 head B, and is provided at its outer end with a half-clutch or series of teeth that can be engaged with corresponding teeth, or a half-clutch upon the end of a longitudinally-movable sleeve, K, mounted on shaft F, and fitted 75 thereto with a spline or feather, *f*, so as to rotate with said shaft. At the outer end of the sleeve K, rigidly fixed upon or integral therewith, is a hub, *l*, in which are fixed the hand-levers L, for turning the shaft when the power devices are not in clutch therewith. A 80 gear, J', is mounted on the sleeve K in a manner to revolve therewith, which gear can be moved into and out of mesh with an intermediate gear, M, supported on a stud, *m*, at the 85 side of the head, as indicated. The gear K' may be made longitudinally movable on the sleeve K, and be fitted thereto with a spline or feather, *v*, to insure simultaneous rotation, as indicated in Fig. 3; or, if preferred, said 90 gear K' and sleeve K may be rigidly connected or formed integral with each other, as indicated in Fig. 4.

A short shaft, *n*, is mounted in a suitable bearing in the head B, as indicated. (See Fig. 95 3.) Upon one end of said shaft is fixed a gear, N, that meshes with the rack A' on the upright or frame A, while upon its other end is fixed a gear, P, that meshes with the intermediate gear, M. Any convenient device may 100 be employed on the head for clamping it to the ways *a*, if desired, or the head may be free

to be held by the gear n in the rack A' , as shown.

In the operation, assuming the worm-wheel G to be at work or in rotative action, then, by 5 moving hub H into clutch therewith, rotation is imparted to shaft F and sleeve K . Now, if gear K' is slipped into mesh with gear M , the motion is transmitted through gears M and P and shaft n to the gear N , which latter, by roll- 10 ing up or down the rack A' , raises or lowers the head B on the upright A , together with the parts connected therewith. If, on the other hand, the gear K' is left out of mesh with M , and the sleeve K is moved into clutch 15 with sleeve J' , then motion is imparted to the gear J , which, acting upon the rack C' , causes the quill C and drill-spindle D to move up or down, the head B remaining stationary. Again, the parts K and J' being in clutch, 20 and the gear K' slipped into mesh with M , then gear N effects movement of the head, while gear J effects movement of the quill, the feed up or down being thus compound, and the speed consequently doubled. With 25 the gear K' integral or fixed on sleeve K this latter operation could not be obtained, as said gear K' would move in or out positively with the clutching-sleeve K .

By the levers L the mechanism can be 30 worked by hand in similar manner to that described, the clutch H being first slipped out to release the wheel G .

The head and quill may be provided with a lever counterbalance device, T , arranged to 35 act in the customary manner.

I am aware that drilling-machines have heretofore been made wherein the upright frame is provided with a rack upon which the head is geared; also, that other styles of drilling-machines are provided with feed-racks on 40 the quill. Therefore, I do not herein claim such construction, broadly. So far as I am aware, however, none of the former drilling-machines have combined therewith devices for inter-

changeably feeding by the head or the quill 45 at will.

What I claim as of my invention, and desire to secure by Letters Patent, is—

1. An upright drilling-machine provided with feed-racks, both on the upright frame 50 and the quill, in combination with operating-gearing and shifting-clutches mounted in connection with the head, and connecting said racks with the power feed-shaft, substantially as hereinbefore described, whereby automatic 55 feeding of the drill is interchangeably effected either by action of the head upon the upright or by action of the quill in the head, as set forth.

2. The combination, with the drill-spindle, 60 quill C , having rack C' , upright frame A , having rack A' , and head B , of the shaft F , the clutch-sleeve J' , carrying gear J , loose on said shaft, the clutch-sleeve K , splined to said shaft and having a gear, K' , mounted thereon, the 65 gear N , meshing with rack A' , the shaft n , and the gears F and M , substantially as and for the purposes set forth.

3. The combination, with the gears M , P , and N and shaft F , of the sleeve K , fitted on 70 said shaft with a spline, f , and the gear K' , longitudinally movable upon and fitted to said sleeve by a spline, v , substantially as and for the purpose described.

4. In combination, substantially as de- 75 scribed, the head B , drill-spindle D , quill C , with rack C' , the worm-wheel G , clutch-hub H , shaft F , clutch-sleeve J' , with gear J , clutch-sleeve K , gear K' , hand-levers L , gears M , P , and N , shaft n , and rack A' , substan- 80 tially as and for the purposes set forth.

Witness my hand this 17th day of February, A. D. 1886.

ALBERT F. PRENTICE.
